Pierre Barnes
ATTORNEY

UNITED STATES PATENT OFFICE.

DAVID W. SOLOMON, OF ARLINGTON, WASHINGTON.

SAW-HANDLE.

SPECIFICATION forming part of Letters Patent No. 752,364, dated February 16, 1904.

Application filed June 2, 1903. Serial No. 159,726. (No model.)

To all whom it may concern:

Be it known that I, DAVID W. SOLOMON, a citizen of the United States, residing at Arlington, in the county of Snohomish and State of

5 Washington, have invented certain new and useful Improvements in Saw - Handles, of which the following is a specification, reference being had therein to the accompanying drawings.

10 This invention relates particularly to handles for crosscut-saws.

The object of the invention is to provide an improved construction of handle for securely holding a saw - blade which will be simple, 15 strong, and easy of adjustment and whereby greater ease is secured to the operator and his hands are guarded from being accidentally lacerated by coming in contact with the teeth of the saw.

20 The accompanying drawings, forming part of this specification, represent what I consider the best means of carrying out the invention and attaining the above-mentioned objects, in which—

25 Figure 1 is a side elevation of the handle attached to the end of a saw-blade. Fig. 2 is a plan view of the same. Fig. 3 is a perspective view of one of the clamping-screws shown in the other views.

30 In the said drawings the letter *a* indicates a socket for the reception of a handle-stick *b* and is integrally connected by a shank *c* to a plate *d*, which is bifurcated, as plainly shown in Fig. 2, to provide a slot *e* to receive the end 35 of a saw-blade *S*. The plate *d* is extended downwardly to provide a hand-guard *d'*.

The handle is affixed to the saw - blade by means of clamp-screws *f* and *f'*, having, preferably, rectangular-shaped middle portions *W*, 40 that are passed transversely through apertures *g* and *g'*, respectively, of the plate. The said apertures are made, preferably, of similarly-shaped sides, so as to prevent their being rotated as the wing-nuts *k* thereof are screwed 45 down upon the threaded ends of the bolts in

clamping the handle upon the saw. The aperture *g* is elongated to permit the clamp-bolt therein being positioned to most effectually hold the said blade of any width.

When the saw is to be used by a single operator, the handle would be placed upon the saw-blade, as shown in Fig. 1, with the guard extension *d'* projecting beneath a line extended along the points of the saw-teeth and which prevents the operator's hand being cut should it be thrust forward independently of the saw when for any reason the blade gets stopped within the saw-kerf.

Where the saw is used by two men—as, for example, in felling trees—then the handle may advantageously be reversed—that is to say, the guard extension would be toward the back of the saw, where it may be used as a supplemental hold for one of the hands of the operator in guiding the saw and also to form a fulcrum, whereby the sag of the saw in horizontal cuts may be obviated by pressing down with one hand upon the stick-handle and bearing up with the other upon the guard.

It is obvious that this handle while being 70 retained in the same plane as the blade may be inclined to any angle relatively of the axis of the blade, as the handle-clamping bolts are not engaged in any holes of the blade, and in this particular, as well as to other advantages 75 above referred to, the invention marks a decided advance in the art.

Modification may be made without departure from the principle or sacrificing the advantages of the invention.

Having described my invention, what I claim as new, and desire to secure by Letters Patent, is—

1. In a saw-handle, the stick-socket connected integrally by a shank with a bifurcated plate 85 having apertures extending therethrough for the reception of clamping-bolts, whereby the divided part may be drawn together to embrace a saw-blade, one of said apertures being elongated, whereby the said bolts may be rela- 90

tively positioned so as to accommodate saw-blades of varying widths therebetween and the said clamping-bolts, substantially as specified.

- 5 2. In a saw-handle, the combination with a stick-socket *a*, shank *c*, plate *d* having a slot *e* and apertures *g* and *g'* and provided with a hand-guard *d'* in combination with clamp-bolts

f and *f'* and the nuts *h*, substantially as and for the purposes described. 10

In testimony whereof I affix my signature in presence of two witnesses.

DAVID W. SOLOMON.
